UNITED STATES PATENT OFFICE.

WILLIAM S. HALLOWELL, OF WYNCOTE, PENNSYLVANIA.

BOOT, SHOE, OR SLIPPER HOLDER.

SPECIFICATION forming part of Letters Patent No. 632,409, dated September 5, 1899.

Application filed January 13, 1899. Serial No. 702,091. (No model.)

To all whom it may concern:

Be it known that I, WILLIAM S. HALLOWELL, a citizen of the United States, residing at Wyncote, in the county of Montgomery, 5 State of Pennsylvania, have invented a new and useful Improvement in Boot, Shoe, or Slipper Holders, which improvement is fully set forth in the following specification and accompanying drawings.

This invention has reference to a novel construction in a shoe-holder; and it consists of an inexpensive device of this character which can be readily applied to a door or similar support, which is longitudinally adjustable 15 to vary its capacity, and in which the supporting parts are relatively adjustable to accommodate shoes of different size.

The invention further consists in the features of construction and combination of parts 20 hereinabove fully described, and particularly pointed out in the claims.

Figure 1 is a front elevation of a shoe-holder constructed in accordance with this invention. Fig. 2 is an end elevation thereof. Figs. 3 and 25 4 are sectional views taken, respectively, on lines $x\ x$ and $y\ y$ of Fig. 2. Fig. 5 is a longitudinal section of an end portion of one of the supporting-rods. Fig. 6 is a fragmentary view in elevation and in section and illustrating 30 a modification.

Similar letters of reference indicate corresponding parts in the figures.

Referring to the drawings, the holder consists, essentially, of rear supports situated one 35 above the other and an adjustable front support that is situated between and in front of said rear supports. The rear supports are arranged so that the upper one thereof engages the heel of the shoe, while the sole rests 40 against the lower rear support. The adjustable front support engages the upper portion of the shoe at about the instep to hold the same in any desired position against the rear supports and can be either automatically adjustable 45 to accommodate itself to shoes of varying sizes and to hold the same under pressure or it may be adjustable, so as to be set previously and in conformity with the size of shoe to be held. The rear supports can be 50 provided in various ways, but consist, preferably, of two transverse rods A and B, carried by end brackets C, the latter to be secured to

the door, wall, or the like to which the rack is applied. The upper rod A is near the upper end of the bracket and a little distance in front of the lower rod B, near the lower end thereof. The adjustable front support consists of a rod D, parallel with rods A and B, but situated between the same. As before stated, this front support D may be adjustable automatically, as best shown in Fig. 2, or it may be adjustable by means of a set-screw, as shown in Fig. 6, hereinafter referred to. In the particular construction shown in Figs. 1 to 4 the end brackets C are provided with upwardly and rearwardly inclined guides or slots E, and at the upper ends of the slots are barrels F, open at their lower ends and in which are situated the springs G. The ends of the front support or rod D pass through the guides E and are secured to the lower ends of the springs G, the upper ends of the latter being secured at the upper ends of the barrels F. Since the springs G act by contraction, they serve to draw the rod D toward the upper ends of the guides or slots E. The said rods A, B, and D are also longitudinally adjustable to vary the length and capacity of the holder, such adjustability being attained by making the rods telescopic, as shown in Fig. 5, the rods proper being tubular and receiving the spindles H, as shown. The ends of the rods, as well as the spindles, are provided with heads and collars K, the latter abutting against the outer faces of the brackets C, as shown.

The operation is as follows: The holder is placed in position by securing the brackets C against the door or the like, it being noted that no other preparation is necessary to adapt the rack for use. The shoes to be supported are inserted, toes downward, in the rear of the front support D, which moves downwardly and accommodates itself to the size of the shoe, as shown in dotted lines in Fig. 2. The front side of the heel rests upon the upper support A and the sole of the shoe against the lower support B. The tension of the springs G not only allows the front support to accommodate itself to the size of the shoe, but also maintains the pressure upon the shoe to hold it in position.

It is obvious that shoes can be as readily removed as inserted, that the device will ac-

commodate slippers and shoes regardless of the uppers, that the shoes are held so that a free circulation of air around the same is possible to keep them dry, and that the rack is 5 light and not unattractive in appearance.

As shown in Fig. 6, the springs can be dispensed with and the rod L secured in place by the thumb-nut M upon the threaded end N thereof, it being also obvious that said 10 threaded ends can pass through slots or guides in brackets or through a plurality of openings made for this purpose.

Having thus described my invention, what I claim as new, and desire to secure by Letters 15 Patent, is—

1. In a shoe-holder, stationary rear supports situated one above the other, a yielding front support situated between and in front of the same, and end brackets common to said 20 supports.

2. In a shoe-holder, two stationary rear supports situated one above the other, a front

support movable vertically and laterally between and in front of said rear supports, resilient means for moving said front support upwardly and rearwardly, and end brackets 25 common to said supports.

3. In a shoe-holder, the upper and lower rear supports, an adjustable front support situated between and, in front of the same, 30 said rear and front supports being longitudinally adjustable, and end brackets common to said supports.

4. In a shoe-holder, the end brackets, upper and lower rods mounted at the rear thereof, inclined guides at the front of said brackets, a rod mounted to slide in said guides, and springs for moving said rod toward the upper 35 rear ends of said guides.

WILLIAM S. HALLOWELL.
